(57) **CLAIM**

The ornamental design for a meat processing machine, as shown and described.

DESCRIPTION

FIG. 1 is a right, front-perspective view of a meat processing machine, showing my new design.

FIG. 2 is a left side view of the meat processing machine.

FIG. 3 is a front view of the meat processing machine; and,

FIG. 4 is a rear view of the meat processing machine.

The broken lines shown in the drawings represent portions of the meat processing machine that form no part of the claimed design.
